UNITED STATES PATENT OFFICE.

EDWARD LINCK, OF PHILADELPHIA, PENNSYLVANIA, ASSIGNOR OF ONE-HALF TO
FRANK LYSTER, OF PHILADELPHIA, PENNSYLVANIA.

METALLIC WINDOW.

1,198,244.

Specification of Letters Patent. Patented Sept. 12, 1916.

Application filed June 23, 1915. Serial No. 35,742.

To all whom it may concern:

Be it known that I, EDWARD LINCK, a citizen of the United States, residing at Philadelphia, county of Philadelphia, State 5 of Pennsylvania, have invented a new and useful Metallic Window, of which the following is a specification.

10 My invention relates to a new and useful metallic window and consists in providing means for assembling and securing the parts together whereby the window can be sent in knock-down condition and set up in the window openings of a building.

It further consists of other novel features of construction, all as will be herein-after fully set forth.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 is a vertical section of a metallic window, embodying my invention, showing the parts broken away. Fig. 2 is a vertical sectional view of portions of the parts shown in Fig. 1 and with a wind shield and coacting parts connected therewith. Fig. 3 is a horizontal section of a portion of the window frame and sashes seen in Fig. 1. Fig. 4 is a partial side elevation, partial vertical section of the upper portion of the window frame seen in Fig. 1, and illustrating more particularly the manner of securing the sash pulley housing to the window frame. Fig. 5 is a partial side elevation and partial vertical section of the parts seen in Fig. 4 at right angles thereto. Fig. 6 is a plan view of the parts seen in Fig. 5. Fig. 7 is a perspective view, in detached position, of a metallic plate and flange employed to connect certain of the parts. Fig. 8 is a perspective view of a fastening device employed. Fig. 9 is a plan view of a blank to be formed into a cup or pocket, as illustrated in Fig. 10. Fig. 10 is a perspective view of a cup or pocket for re-

taining certain of the fastening devices employed. Fig. 11 is a horizontal section, on an enlarged scale, of a portion of the mullion and rim or cover therefor, showing the manner of connecting the parts. Fig. 12 is a front elevation of a portion of the mullion. Fig. 13 is a vertical section of a portion of one of the pockets of the mullion, on an enlarged scale, showing the manner of connecting the division bar therein. Fig. 14 is a front elevation of a complete window frame and sashes on a reduced scale. 55 60 65

Similar numerals of reference indicate corresponding parts in the figures.

Referring to the drawings, 1 designates the sill of the window frame which is formed of sheet metal of a single piece and which is suitably bent to form vertical walls 2 and 3 having the inwardly turned flanges 4 at the bottom which are adapted to rest on the bottom wall 5 of the window opening, the upper wall of the sill being bent to form the top surfaces 6 and 7 which, as here shown, are on different levels formed by bending the metal at 8, the bottom of the window-frame sashes contacting with these surfaces at the proper time, as will be evident. It will be understood that the sill extends across the window opening with the ends thereof seated in suitable recesses 9 formed in the wall 10 of the window opening. Suitably secured to the sill adjacent each end thereof is a metallic plate 11 which, as here shown, has an end flange 12 extending upwardly therefrom and the side flanges 13 and 14, said plate being secured to the sill by the screws 15, by which means it will be understood that the said sill is provided with upwardly extending flanges, as will be evident.

In contact with the sill are the jambs 16 of the window-frame only one of which is illustrated, see Fig. 3, and as here shown each jamb is formed of sheet metal bent to form the end walls 17 and 18 and with the ends of the metal bent inwardly to form the members 19, it being noted that a suitable portion of the end walls 17 and 18 and the members 19 are seated in the recess 9 of the window opening. The metal comprising the jamb is bent at the opposite or outer side to provide the shoulders 20 and

21 and a division strip 22, extending outwardly intermediate the shoulders 20 and 21 at substantially the central portion of the jamb in order to form the runways 23 and 24 for the window-frame. The inner walls 25 of the runways are suitably positioned adjacent the flanges 13 and 14 and are secured thereto in a suitable manner in order that the jambs will be properly connected with the sill.

10 As here shown, I have connected the inner wall 25 of the runway with the flanges by screws 26 which pass through suitable openings punched in the flanges, the metal struck from the openings forming threaded bosses 27 with which the screws 26 engage. The end flange 12 of the plate 11 is connected with the end wall 18 of the jamb by a screw 28 which is in similar engagement 15 with a threaded boss 27 thereon. The lintel or head 29 is formed of sheet metal and of a single strip of material bent to form the outer walls 30 and 31 having the inturned portions 32 and with its bottom bent to 20 form shoulders 33 and 34 with a division strip 35 therebetween thus forming suitable pockets for the reception of the window sash frames.

30 The upper edges of the jambs 16 abut the bottom wall of the head 29 and the latter is provided with a slot 36 adjacent each point of contact. In order to connect the jamb 15 and head 29, I provide a pulley housing 37 which is formed of a U-shaped 35 portion 38 having bearings 39 for the journals of the sash pulley 40 and one side of which housing is provided with a flange 41 extending horizontally therefrom and secured to the inner side of the head 29, while 40 a second flange 42 extends angularly and downwardly from the housing 37 and through the slot 36 and is secured to the side wall of the jamb 15. In the present instance, I have shown the screws 43 for securing the parts together and have struck up the metal of the flanges to form the openings and to provide the bosses 44 for threaded engagement with the screws 43. By this means it will be understood that 45 the sill can be placed in position in the window opening after which the jambs are inserted in the side recesses resting upon the sill and are secured to the flanges of the plate 11 which are secured to the sill and thereafter the head or top can be secured to the jambs by means of the pulley housing just described.

50 In the construction of a metallic window wherein two pairs or more of sashes are desired, I employ a mullion and for this purpose I connect a plate 45 with the sill 1, intermediate the end plates 11, by means of screws 46, said plate having an end flange 47 and pairs of flanges 48 and 49 on the 55 opposite sides thereof extending upwardly

therefrom, as seen in Figs. 3 and 7, each of the flanges having an opening 50 therethrough and with the metal, struck up from the openings, forming bosses 51 and to the flanges of this plate I connect the mullion.

70 As here shown, the mullion comprises a body portion formed of a single piece of sheet metal, bent to form an end wall 52 having adjacent thereto the outwardly extending shoulders 53 on opposite sides of the body and with the metal bent inwardly to form pockets 54 and the extending end portions 55, the said pockets 54 being formed on opposite sides adjacent the center of the mullion. The body portion can 80 be slipped or slid on to the flanges of the plate 45 and can be secured to the same by screws 56 the flange 47 being secured to the end wall 52 and the side flanges to the sides of the mullion body in order that the said 85 body portion of the mullion will be suitably secured to the sill. The upper ends of the sides of the mullion abut the head 29 which is provided with suitable slots similar to slots 36 adjacent the point of contact of the said side walls and a pair of pulley 90 housings 37 will be suitably connected with the head by the flange 44 and each is provided with a flange 42 extending downwardly through a slot 36 of the head, to be 95 connected each with a side wall of the body of the mullion. From this it will be understood that the mullion is connected with the head in a similar manner to the connection of the jambs and head.

100 Removably secured within the pockets 54 are the division strips 57 formed of metal bent U-shaped and which project sufficiently beyond the pockets to form runways and to engage the side walls of the 105 window-frame sashes. As here shown, I have connected the division strips by screws 58 which pass through suitable openings in the inner wall 59 of the pocket and a nut 60 is engaged with the threaded end of the 110 screws 58 for holding the same in position. In order to lock the nuts against movement, I have provided a cup 61, see Fig. 10, which is provided with the side walls 62 and with the flanged walls 63, the cut being formed 115 from a blank, as shown in Fig. 9, and being suitably bent along the dotted lines, as will be evident. The base 64 of the cup 61 is provided with an opening 65 through which the ends of the screws 58 project. The inner walls 59 of the pockets of the mullion are provided with suitable slots 66 into which the flanges 63 are inserted after the nut is tightened and the ends of the flanges are bent to engage the inner side of the said 120 inner wall 59 thus serving to lock the nut against movement. Removably secured to the ends 55 of the body of the mullion is a removable rim or cover 67 which is formed of sheet metal suitably bent to provide the 125 130

walls 68 on each side of the body portion which form shoulders and which, with the division strips 57, form a runway for one window sash frame, while shoulders 53 and strips 57 form a runway for the other window sash frame. In order to removably connect the cover 67 the ends of the members 55 of the mullion body are provided with an opening 69 and with the slots 70 and a screw 71 having its head in engagement with a suitable portion of the removable cover passes through the opening 69 and is engaged by a nut 72 which is held against movement by a cup 61 similar to that previously described. From this it will be understood that the mullion is secured to the flanges of the plate 45 at the building and after the outer sash has been placed in position the division strips are secured to the mullion after which the inner window sash is placed in position and the cover 67 is then secured in place by which means the parts can be readily assembled, as will be evident.

It will be noted that the connection of the body of the mullion to the flanges of the plate 45 is made at the inner walls of the runways. The window sash frames comprise the bottom rail 73 formed of sheet metal and of suitable shape and bent to provide a pocket 74 for the reception of the glass 75 and the upper rail 76 formed of sheet metal is bent to form a pocket 77 which is of suitable extent in order that the glass 75 may be inserted therein and pushed upwardly until it passes the top 78 of the bottom rail 73 after which the glass can be lowered into the pocket 74, the position thereof being best understood in Fig. 1.

Connected in a suitable manner with the top and bottom thereof are the side rails of the sash which comprise a body portion formed of sheet metal bent to provide on one side a shoulder 79 extending outwardly beyond the wall 80 of the body and with the side member 81 provided with a suitable opening.

82 designates a removable cap for the side rails bent to form a shoulder 83 and having a flange 84 extending adjacent the wall 81 of the body when in position, said flange being also provided with an opening and through which and the opening in the member 81 passes a threaded bolt 85 which is secured in any suitable manner to the wall 80 of the body of the side rail. A nut 86 is engaged with the threads of the bolt to lock the cap 82 in position. By this means it will be understood that by removing the nut 86 the cap 82 may be removed and the glass 75 inserted in position after which the cap 82 can be secured to the side rails, the shoulders 79 and 83 serving to hold the glass properly in position.

87 designates a muntin bar which may be

employed which consists of the body portion formed of sheet metal bent to form the oppositely extending shoulders 88 and 89 and having the flanges 90 and 91 extending angularly therefrom in suitable relation to each other.

92 designates a stiffening bar seated between the flanges 90 and 91 and said flanges and stiffening bar are secured together by a split bolt 93 having the arms 94 and 95 extending on opposite sides of the flanges and having suitable openings 96 through which passes a screw or other fastening member 97 which likewise passes through suitable openings in the flanges 90 and 91 and the stiffening bar 92, for locking the parts together, it being noted that the said bolt 93 is provided with a threaded end 98.

99 designates a removable cap for the muntin bar which is formed of sheet metal bent to form shoulders 100 and 101 and which is provided with a suitable opening through which the threaded end 98 of the split bolt 93 passes and is adapted to receive a nut 102 in order to removably lock the cap and the muntin bar, it being noted that the oppositely situated shoulders 88 and 100 and 89 and 101 serve to hold the glass in position. By removing the nut 102 the cap can be removed and the glass 75 inserted in position after which the cap may be again secured in place to properly hold the glass.

At suitable points in the top 29 I provide pairs of openings 103 and 104 each pair being in suitable relation to a pulley 40 and through which the chain 105 passes one end being connected with the top rail of one sash and the other end being suitably connected with the top rail of the other sash, whereby it will be understood that when one sash is raised the other will be lowered. As will be seen in Fig. 1, I may if desired provide a turnbuckle 106 which is in threaded engagement with the hooks 107 one of which is suitably connected with the chain 105 and the other of which is suitably connected with a top rail of the window sash this device being used for regulating the length of the sash chains when adjusting the sashes.

In some instances I have found it desirable to employ an adjustable wind shield for the windows and for this purpose I have provided a quadrant 108 which is connected with the side jamb of the window frame and which has a slot 109 in which moves a clip 110 which carries a set screw 111 for locking the clip in its different positions. Pivotedly connected with the sill is a frame 112 which as shown carries a glass 113 and which is in suitable connection with the clip 110 in order that the frame and glass can be moved to opened or closed position, as desired. The upper end of the frame 112 is provided with a flange 114 which when 130

the sash is correspondingly raised will abut against the same, as seen in dotted lines, Fig. 2, to prevent passage of any air.

It will now be apparent that I have devised a metallic window by means of which the parts can be shipped from the place of their manufacture to their destination in knock-down condition and can be readily and quickly assembled at the building and 10 the sash frame can be immediately removed as desired. The novel construction of the side rails and muntin bar of the window sashes provide a construction by means of which the window glass can be inserted and 15 removed as desired.

It will now be apparent that I have devised a novel and useful construction of a metallic window which embodies the features of advantage enumerated as desirable 20 in the statement of the invention and the above description, and while I have, in the present instance, shown and described a preferred embodiment thereof which will give in practice satisfactory and reliable results, it is to be understood that the same 25 is susceptible of modification in various particulars without departing from the spirit or scope of the invention or sacrificing any of its advantages.

30 Having thus described my invention, what I claim as new and desire to secure by Letters Patent, is:—

1. A metallic window comprising a sill, a lintel, plates secured to said sill and each 35 having an upwardly extended end flange and side flanges, jambs, said lintel having a slot adjacent the points of contact of the jambs with the bottoms of said lintel, and a pulley housing above each jamb having 40 journals for the pulley, said housing being secured to the flanges of one of said plates and having a horizontally extended flange secured to the inner side of the lintel.

2. A metallic window comprising a sill, 45 a lintel, plates secured to said sill and each having an upwardly extended end flange

and side flanges, jambs, said lintel having a slot adjacent the points of contact of the jambs with the bottoms of said lintel, and a pulley housing above each jamb having 50 journals for the pulley, said housing being secured to the flanges of one of said plates and having a horizontally extended flange secured to the inner side of the lintel and 55 having a downwardly extended portion secured to the side of the jamb.

3. A metallic window comprising in combination, a sill, a lintel formed of sheet metal, metallic plates secured to said sill each having an upwardly extending end 60 flange and side flanges, jambs formed of sheet metal, the lintel having a slot situated adjacent the points of contact of the jambs with the bottom of the lintel and a pulley housing above each jamb formed 65 of a single piece of material having journals for the pulley, said housing being secured to the flanges of one of said plates and having a flange extending horizontally from the housing and secured to the inner 70 side of the lintel and having a flange extending downwardly through a slot and secured to the side of the jamb.

4. A metallic window comprising a sill, a lintel, plates secured to said sill and each 75 having an upwardly extended end flange and side flanges, jambs, said lintel having a slot adjacent the points of contact of the jambs with the bottoms of said lintel, and a pulley housing above each jamb having journals for 80 the pulley, said housing being secured to the flanges of one of said plates and having a horizontally extended flange secured to the inner side of the lintel, said jambs being bent to form shoulders and the flanges of 85 said plates being at an angle to each other and disposed adjacent said shoulders.

EDWARD LINCK.
